UNITED STATES PATENT OFFICE.

CHARLES H. MORRILL, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

MANUFACTURE OF BELLOW-TONGUE OVERSHOES.

1,369,260.

Specification of Letters Patent. Patented Feb. 22, 1921.

Application filed April 14, 1919. Serial No. 289,869.

To all whom it may concern:

Be it known that I, CHARLES H. MORRILL, a citizen of the United States, residing at Swampscott, in the county of Essex and State of Massachusetts, have invented certain Improvements in the Manufacture of Bellows-Tongue Overshoes, of which the following description, in connection with the accompanying drawings, is a specification, like reference characters on the drawings indicating like parts in the several figures.

This invention relates to the manufacture of footwear and more especially it concerns rubber footwear of the kind known as "arctics," particularly that type having high leg portions provided with bellows-tongues employing several, commonly four, buckles or equivalent fastenings.

Ordinarily the upper or top of an arctic overshoe of the type referred to comprises among other parts an inner fleece lining, an intermediate reinforcing layer, and an outer fabric called a cashmere. Commonly in making the arctic the various top pieces are separately and successively positioned and applied to a wooden form or last, the maker fitting and lapping the pieces as the "building up" process progresses. Thereafter the shoe bottoming materials, including the insole, filler, foxing and outsoles, are applied, after which the article, including the form, passes to the vulcanizing oven.

The time required to make a shoe under the method referred to is necessarily affected by the number of separate pieces which have to be cut and assembled, and the durability and water-proof qualities of the shoe are also affected thereby, since the greater the number of joints between the pieces, the greater is the liability of some defective joint giving away.

The present invention has for one of its objects the production of a bellows-tongue arctic with a lesser number of separate pieces and joints than heretofore employed, with a view to making overshoes of this type which will be as nearly seamless as possible and at the same time uniformly well-fitting, and with a view to saving time in making the shoe and increasing the water-proof durability thereof.

One objection to the usual bellows-tongue arctics is that in order properly to shape the shoe the part of the upper comprising the

vamp and front of the leg or top is made of at least three pieces having two vertical joints or seams. These joints extend to the bottom of the "bellows" and although usually so located that they are covered by overlying portions of the "bellows" when the arctic is buckled, do not reliably exclude moisture, since snow frequently finds its way under the overlying folds of the bellows, and becomes packed thereunder so that, when the snow is partially melted by the warmth of the foot, there is a tendency to force water through such joints. A further object of my invention is to provide arctics of the high "bellows tongue" type which will be entirely free from joints low enough to permit leakage, as from walking in snow.

As exemplified in the accompanying drawings, this object is attained by making the vamp and the front of the top or leg of only two pieces joined together on a line transverse to the height of the shoe, the one seam or joint being at substantially the top of the ankle portion of the shoe and preferably so curved that this portion of the upper can be sprung into the reentrant curve of the form. This substantially horizontal joint extends across those portions of the upper which form the wings of the bellows. The result is that vertical seams are eliminated, there are no seams low enough to be subject to attack by snow packed under the wings when the shoe is buckled, and a more economical cutting of the fabric can be made.

Coincident with the above mentioned advantages is the further one that the constituent pieces of the vamp may be assembled and rolled while flat, the same may be done with the pieces which comprise the facing or front of the leg, and also with those pieces which comprise the quarter and back of the leg, and then these three sections fastened together may be placed upon a form, for example, as described in my application filed January 16, 1919, Serial No. 271,397, and the operations of pulling-over, lasting and sole laying performed, to which application reference may be had for a more detailed description of advantages such as the saving of hand labor and enabling a more accurate and uniform production to be obtained at low manufacturing cost.

A further object of the present invention

is to facilitate manipulation during the manufacturing steps, particularly during the pulling-over and sole laying, and to reduce the weight of the materials to be handled up to the point of vulcanization. In this aspect, the invention utilizes a two piece form which is separable to provide a foot portion and a leg portion, and employing only the foot portion for the manufacture 10 of the shoe prior to vulcanizing it, thereby avoiding objectionable weight and possible interference with the machine operations of pulling-over, etc., such as are described in the application referred to. After the shoe 15 is completed except for vulcanization, the leg portion of the form is inserted and connected to the foot portion to prepare for the vulcanizing step.

Heretofore the folding of the wing or bellows portions of an arctic of the type referred to, and the closing of the buckles, to cause the top of the arctic to completely inclose, and conform to, the wooden last or form, has frequently resulted in incorrect 20 folding of the bellows, which incorrect folding is then rendered permanent by the vulcanization. To insure proper folding and to hold all sections of the bellows in correct 25 and smooth relative positions during the vulcanizing, is another object of this invention. I attain this object by the employment of a 30 crease former such as a shell of thin metal, shaped to conform to the curvatures of the front portion of the inner form, the rear edges of its sides being located to define the 35 rear creases of the bellows. This shell is preferably fitted in place after completion 40 of the building of the shoe and the insertion of the leg portion of the form, and the sides 45 of the upper or bellows-wings are then buckled over the shell.

A further characteristic advantage of this 50 feature of the invention is that the shell protects the bellows-tongue from the buckles 55 during vulcanization so that the buckles can not leave impressions in the surface of the fabric of said tongue.

Other objects and novel characteristics of 60 the present invention will now be described 65 in connection with the accompanying drawings, which illustrate one form of shoe manufactured according to my invention, the parts employed, and the method which may be practised in carrying out my improvements, and the invention will then be pointed out in the appended claims.

Figure 1 is a plan view of the vamp and the ankle or leg facing section of the shoe, 70 laid out flat in spaced relation so as to show 75 the shape of the pieces as they are died out. It will be noted that a portion of the cashmere material of the leg facing has been 80 torn and lifted up to expose part of the fleece lining 50, the full outline of which is indicated by the dot-and-dash lines, as well as to

expose part of the reinforcing layers 51 of the wings 17, 18. It will be understood that the fleece lining 50 as well as the reinforcing layers 51 are really continuous across the butt-joint 19 in the finished arctic, although 70 for purposes of illustration they have been shown in this figure as severed on the line of the butt-joint;

Fig. 2 is a perspective view of the inner and outer forms which may be employed, the 75 parts being separated from each other;

Fig. 3 represents a transverse section of the shoe when assembled with the parts of the apparatus shown in Fig. 2, the line of said Fig. 3 being in a plane just above the 80 top of the foot form;

Fig. 4 is a perspective view of the shoe upon the inner form with the wings of the bellows open;

Fig. 5 is a view similar to Fig. 4 but illustrating the crease former or outer former in place, the whole being in condition for vulcanization.

The cashmere vamp section 12 of the shoe and the cashmere front of the ankle section or leg facing 13 are shown in Fig. 1 as laid out flat. In the process of manufacturing the arctic they are brought together so as to form the butt-joint 19 (Fig. 1), this butt-joint being backed by three pieces each 90 of which extends across the butt-joint. One of these pieces is the fleece lining 50, the outline of which is shown in dot-and-dash lines, said piece extending from the top of the leg facing 13 nearly to the bottom of the vamp 100 12 and being cemented to the inside faces of the pieces 12 and 13. The other two pieces are the reinforcing layers 51. Each of these layers is cemented to the inside face of a completed wing 17, 18 so as to act like 105 the fleece lining 50 as backing for a portion of the butt-joint 19 and is also cemented to the inside face of one side of the quarter 14.

In the present invention as exemplified in the drawings the vamp 12 is provided with 110 wings 17 and the facing section 13 is provided with wings 18 which, when the shoe is built up to the condition shown in Fig. 4, are secured by cement to the side margins 115 of the section 14, said wings or margins forming part of the bellows of the arctic. After the top of the arctic including the vamp, leg facing and quarter have been fastened together as described, the foxing 15, 16 is attached by cement.

The only seam or joint in the entire shoe through which any leakage of moisture could possibly occur is the joint 19 where the upper edge of the vamp 12 and the lower edge of the facing 13 abut. This joint or 125 seam extends to the side edges of the sections 12 and 13 so as to include the bellow wing portions 17, 18. It is to be understood, as has been explained above, that when the parts of the shoe are put together 130

the usual reinforcing material 51 and fleece lining 50 lying under the outer cashmere material extends across the joint or seam 19 to make that joint or seam impervious to 5 moisture in substantially the same manner as practised in rendering all butt seams of articles of footwear of this type waterproof.

Connected to the forward edges of the 10 quarter are suitable fastenings such as buckles of a usual type comprising tongue members 20 and slotted keeper members 21. In Fig. 2 I illustrate an inner form comprising a foot form 22 and an ankle or leg form 23, these two sections being separably connected. The upper or ankle form 23 is provided with a downwardly extending dowel 24 adapted to fit a hole 25 in the foot form 22. Said foot form has two upwardly 20 and outwardly inclined spring dowels 26 adapted to engage inclined keeper sockets in the member 23. The dowels 26 are held projected as indicated in Fig. 2 by springs not necessary to illustrate, so as to remain 25 engaged with the keeper sockets 27 when the members 22, 23 are brought together with the dowel 24 engaging the hole 25. The two members 22, 23 may be separated by inserting any suitable instruments 30 through the keeper holes 27 to depress the spring dowels 26 far enough to enable the member 23 to be lifted out of engagement with the dowels so as to be separated from the member 22.

35 In making the shoe all of the parts are assembled and the shoe built up in any suitable way, but preferably according to the method explained in the application hereinbefore referred to, and then placed on the 40 foot form 22, the leg form not being inserted until just prior to the vulcanizing operation. Consequently, the shoe is less heavy to manipulate during the manufacturing steps of pulling-over, lasting and sole laying, and there is less interference with the 45 machines employed during such operations than would be the case if both the leg and foot forms were employed together. After the shoe has been completed except for vulcanization the ankle or leg form 23 is inserted in the upper part of the shoe as indicated in Fig. 4, the spring dowels 26 snapping into the inclined keepers 27. This is done to prepare the shoe for the folding 50 of the bellows portions prior to being subjected to the heat of the vulcanizing ovens.

To insure proper folding and holding of the bellows during vulcanization I apply a device substantially of the form shown at 60 28 in Fig. 2. This device I term an "outer former." It is represented as consisting of a piece of suitable sheet material such as thin metal shaped substantially as shown. It is to be understood however that its middle portion may be omitted although as

hereinafter described the middle portion performs another function. Whether the device 28 is formed of a continuous piece of sheet material, or as a frame, its rear edges 29 serve, when the device is laid against the 70 front portion of the tongue, to push that portion smoothly back against the inner form 22, 23, said rear edges 29 serving to accurately define the lines upon which the 75 wings are folded when the foldable portions of the bellows are closed to the position shown in Fig. 5. This device is left in place during vulcanization and insures retention of the proper folds of the bellows during such vulcanization.

The former 28 is shaped to conform to the curves of the front portion of the shoe its sides being extended rearwardly a sufficient distance to provide for accurate folding of the tongue wings as desired. This close fit 85 insures that the device will not interfere with the proper form of the wing portions which are folded over it when the shoe is buckled and being vulcanized.

The middle portion of the outer form 28 90 serves another purpose of preventing the metallic fastenings from embedding themselves in the uncured material of the bellows tongue of the upper during vulcanization. In other words it acts as a shield which, fitting between the buckles of the shoe and the 95 fabric, prevents said buckles from leaving an impression in the surface of the fabric so that, after the shoe while fitted in connection with both the inner and outer forms 100 as indicated in Fig. 5 has been vulcanized, then when the buckles are separated and the outer and inner forms removed, the bellows wings are not only correctly folded but the portion of the shoe above the instep is in 105 perfectly smooth and unmarred condition.

It is to be understood of course that during the process of building the shoe any suitable reinforcements may be employed, for instance, as indicated in Figs. 4 and 5, 110 reinforcement tabs may be employed as at 30 to strengthen the portions where the vamp and quarter and their foxing overlap.

The overshoe and the method of making the parts thereof and putting them together 115 are not claimed herein but in application Serial No. 417,711, which is a continuation of the present application so far as common subject-matter is concerned.

Having described my invention, what I 120 claim as new is:

1. Means for facilitating the manufacture of rubber overshoes having metallic fastenings, comprising a form for the inside of a shoe and a shield constructed and arranged 125 to fit the front portion of the shoe behind the fastening thereof.

2. Apparatus for use in the manufacture of bellows-tongue overshoes, comprising a form for the inside of a shoe and a form 130

shaped to fit the outer surface of the front portion of the shoe and spread said front portion into conformity with the inner form.

3. Apparatus for use in the manufacture of bellows-tongue overshoes, comprising a form for the inside of a shoe and a form shaped to fit the outer surface of the front portion of the shoe and having its rear margins located to define the rear creases of the 10 bellows folds and maintain them in shape during vulcanization.

4. Apparatus for use in the manufacture of bellows-tongue overshoes, comprising, in combination, an internal form and an external form constructed and arranged to 15 hold the bellows portions of the shoe in correct folded condition during vulcanization.

5. A device for insuring correct folds of the bellows-tongue of an overshoe, comprising a former shaped to present its rear portions in positions to define the rear creases of the bellows folds.

6. A device for insuring correct folds of the bellows-tongue of an overshoe, comprising a former shaped to conform to the curves of the front portion of the shoe and having its rear margins relatively located to define the rear creases of the bellows folds.

7. A device for use in the manufacture of bellows-tongue overshoes comprising a shell having a length and shape to fit over instep and leg facing portions of the shoe, the rear edges of the shell being relatively spaced to define the rear creases of the folds at the 35 sides of the shoe.

8. A device for preventing the tongue-fabric of a rubber overshoe from being

marred by the buckles of the shoe during vulcanization, comprising a shield constructed and arranged to fit between the buckle of 40 the shoe and the fabric behind said buckle.

9. A device for preventing the tongue-fabric of a rubber overshoe from being marred by the buckles of the shoe during vulcanization, comprising a shield shaped to 45 conform to the front of the shoe and constructed and arranged to be held in position by the buckles when the latter are fastened.

10. That improvement in methods of making vulcanized rubber foot-wear having bellows-tongues which consists in employing a foot form of less height than the leg portion of the shoe during the manufacture of the shoe prior to the vulcanizing operation, then fitting a leg form into the leg portion 55 of the shoe, folding and retaining the bellows in place, and then vulcanizing the shoe while fitted to said two-part form.

11. That improvement in methods of making rubber foot-wear having metal fasteners 60 which consists in assembling the parts of the shoe upon a form, inserting a shield between the fasteners and the shoe material, closing the fasteners, and vulcanizing the shoe.

12. That improvement in methods of making rubber footwear having bellows-tongues which consists in assembling the parts of the shoe upon a form, applying an outer form in position to define and hold the folds of the bellows, and vulcanizing the shoe while 70 the outer form is in fold-holding position.

In testimony whereof I have signed my name to this specification.

CHARLES H. MORRILL.
